ADHESIVE CONTAINER STOPPER AND
BRUSH

Albert A. Bilbrey, Salem, Oreg.

Application July 12, 1937, Serial No. 153,288

1 Claim. (Cl. 91—67.2)

The invention relates to an adhesive container stopper and brush and more especially to glue, mucilage or cement applicator brushes and stoppers therefor.

5 The primary object of the invention is the provision of a stopper and brush of this character, wherein the stopper holds the brush within a container or receptacle for glue, cement or mucilage to avoid the admission of air into said 10 container or receptacle when the brush is not in use for applying the glue, cement or mucilage to a piece of work and in this manner eliminating the hardening of the contents of the container or receptacle.

15 Another object of the invention is the provision of a brush and stopper of this character, wherein the brush can be readily loosened from the contents of a container or receptacle for glue, cement or mucilage without the necessity of 20 grasping such container or receptacle in order to extract or remove the brush therefrom.

A further object of the invention is the provision of a brush and stopper of this character, wherein the construction and the assembly of the 25 same with each other are novel and unique and the brush can be readily and easily freed from the contents of the container or receptacle without undue sticking of such brush, particularly when the contents become hardened about the 30 same and also the stopper renders the container or receptacle airtight when applied thereto and carrying such brush when not in use.

A still further object of the invention is the provision of a brush and stopper of this character, which is simple in construction, thoroughly 35 reliable and efficient in operation, readily and easily manipulated both for closing a container or receptacle and the removal of the brush therefrom for its use, strong, durable, and inexpensive 40 to manufacture.

With these and other objects in view, the invention consists in the features of construction, combination and arrangement of parts as will be hereinafter more fully described, illustrated in 45 the accompanying drawing, which discloses the preferred embodiment of the invention and pointed out in the claim hereunto appended.

In the accompanying drawing the view is a fragmentary vertical sectional view partly in elevation of a brush and stopper constructed in accordance with the invention and applied to a container or receptacle.

Referring to the drawing in detail, A designates generally a portion of a glass container or receptacle, which in this instance is of conven-

tional jar kind having at its open mouth end an externally threaded neck 5 for separable connection therewith of a ring-like rim piece 6 concentrically fitted about a closure cap or cover piece 7 which is separably fitted with said rim piece and has a countersunk center 8 provided with a central opening 9, the peripheral portion of the cap or cover 7 being seated upon the mouth edge of the neck 5 of the container or receptacle A while the rim piece 6 under screw action 10 thereof upon the neck seals the cap or cover peripherally about the mouth or open end of said container or receptacle.

Removably seated in the countersunk center 8 of the cap or cover 7 is a stopper in the form of 15 a spool-like body 10 formed at its outer end with an enlarged knob or head terminal 11 while intermediate of said body 10 is an outwardly bulged circular ledge or an annulus rest flange 12 provided with a concave bottom face 13 concentrically about the body 10 for substantially knife edge engagement or contact as at 14 with the countersunk center 8 of the cap or cover 7. This ledge or flange 12 is next to a rounded inner end 15 of the body 10, the said end 15 being in cross 20 sectional diameter substantially equal to the diameter of the hole or opening 9 in the center 8 of said cap or cover 7 while the ledge or flange 12 is of an outside diameter substantially equal to the diameter of the countersunk center 8 of 30 said cap or cover. The contact 14 of the ledge or flange 12 with the countersunk center 8 of the cap or cover 7 affords an airtight seal to the container or receptacle A when the stopper body 10 is at rest or in closing position on the cap or 35 cover.

The body 10 constituting the stopper has an outwardly tapered center bore or passage 16 therein opening through the outer and inner ends of the same and accommodated within this bore or passage is an outwardly tapered handle 17 of a brush, the bristles or brush end 18 being at the larger end of the handle 17 and is depended within the contents of the container or receptacle A when within the stopper body 10. 40 The smaller end of the handle 17 protrudes a considerable distance outwardly beyond the knob end 11 of the body 10 and has about the same a coiled compression spring 19 contacting with the knob end 11 and a concaved or dished disk-like head or hand hold 20 fixed to the outer end of said handle 17. This spring 19 functions to 45 tension the handle 17 of the brush so that such handle will have a valve plug action within the passage or bore 16 to normally close the same 50 55

and thus eliminate the passing of air from without to within the container or receptacle A through the stopper body 10 when seated upon the cap or cover 17. By compressing the spring 5 19 the handle 17 will be shifted through the passage or bore 16 in the stopper body 10 so as to loosen or displace the bristle or brush end 18 in the contents of the container or receptacle A particularly when such contents has hardened 10 contact with said end 18.

The formation of the stopper body 10 allows hand gripping thereof and finger engagement with the head 20 on the handle 17 of the brush for dislodgment of the end 18 of the said brush 15 in the contents of the container or receptacle A without necessity of the hand grasping of the container or receptacle as is customary when it is desired to remove the brush therefrom and the use of such brush in applying cement, mucilage, 20 glue or the like from within the container or receptacle to a piece of work.

The stopper and brush is particularly adapted for use by shoemakers or shoe repairmen in ap-

plying cement to work and when the said stopper and brush in their assembly with each other are applied to a container or receptacle for the cement, mucilage, glue or the like, the said container or receptacle will be rendered airtight to 5 avoid deterioration of its contents and thus prolonging use thereof.

What is claimed is:

In combination, a receptacle having a centrally perforated and countersunk cover piece, a 10 stopper body fitted in said perforation, said stopper body having adjacent its medial portion an outwardly extending downwardly concaved stopper body, fitted in said perforation, said countersunk area and having a knife-edge arranged to contact said area, an upwardly tapered bore-through said stopper body, a brush having a tapered handle arranged in said bore, and resilient means coacting with the brush and said stopper body to movably hold said handle in said 15 bore.

ALBERT A. BILBREY.
